(74) Attorney, Agent, or Firm — Banner & Witcoff, Ltd.

(57) **CLAIM**

The ornamental design for a display screen with graphical user interface, as shown and described.

DESCRIPTION

FIGURE is a front view of a display screen with graphical user interface showing our new design. The broken line showings of text, the remainder of the display, and the remainder of the graphical user interface form no part of the claimed design. The broken line showing of an electronic device illustrates environmental structure and forms no part of the claimed design.
